ATTORNEY.

UNITED STATES PATENT OFFICE.

GEORGE N. STEERE, OF CRANSTON, RHODE ISLAND.

COMB.

No. 799,762.

Specification of Letters Patent.

Patented Sept. 19, 1905.

Application filed June 20, 1905. Serial No. 266,089.

To all whom it may concern:

Be it known that I, GEORGE N. STEERE, a citizen of the United States, residing at Cranston, in the county of Providence and State of Rhode Island, have invented certain new and useful Improvements in Combs, of which the following is a specification, reference being had therein to the accompanying drawings.

My invention relates to combs for human hair intended to retain the former in position upon the head, and has for its purpose a means of insuring the comb against slipping out of engagement with the hair after insertion therein.

15 A further purpose is to attain the desired end by means of a device which shall be simple, inexpensive, capable of ornamental results, and non-injurious to the engaged strands.

To the above ends my invention consists in 20 an auxiliary hinged or pivoted plate connected to the comb-head and acting in conjunction with the comb-teeth to engage the hair-strands.

Further novel detailed features will appear and be hereinafter claimed.

25 In the drawings which constitute a part of this specification, Figure 1 is a front elevation of a comb embodying my invention in closed position; Fig. 2, a top plan or edge view of the same; Fig. 3, a front view thereof in open position; Fig. 4, a transverse section of the same on line $x-x$ of Fig. 1, and Fig. 5 a similar section on line $y-y$ of Fig. 3.

Like reference-letters indicate like parts throughout the views.

35 In the drawings, a represents the head or base piece, and b the teeth, of a comb. To the rear margin of the head a is fixed by rivets c or otherwise a hinge-plate d , in which is mounted the hinge-pin e and on which is a 40 forwardly-extending tongue f .

A locking or engaging plate g is provided along its lower margin with a plurality of teeth h , directed at right angles to the plate-body. A bearing-plate i is secured by rivets

45 j or otherwise to the upper central inner face of the engaging plate g and supports the ends of the pin e . Fixed by a rivet k or by solder to the inner face of the plate g is a spring-plate l , whose free end is slightly 50 curved and rests against the tongue f of the hinge-plate d .

The operation of my new comb is as follows: The comb is while the parts are in the relative positions shown in Figs. 3 and 5 inserted into the hair, and the hair fills the 55 spaces or intervals intermediate the teeth b adjacent the head g , whereupon the elevated hinged plate g is forced downwardly against the tension of the spring l until the lower margin of said plate overlaps and rests against 60 the upper portions of the teeth and the teeth or projections h , traversing the hair, enter the spaces intermediate the teeth b and are held in engagement therewith by the spring aforesaid. During the downward movement 65 of the plate g the spring l bears against the upper side of the tongue f . When, however, the projections h reach a position adjacent to the teeth b , the spring l bears against the end of the tongue f , and hence operates 70 to press and hold the free edge of the plate g against said teeth b .

By the described means the comb is locked against removal after adjustment in the hair until the wearer desires to manually raise or 75 disengage the plate g .

Having described my invention, what I claim is—

1. The combination with the head and teeth of a comb; of a plate pivoted to the head in 80 position to overlap the upper portion of the teeth, and having projections on its free edge arranged to enter between the teeth, and spring means for holding the free edge of the plate against the teeth. 85

2. The combination of the head and teeth of a comb, a hinge-plate fixed to the head and having an angular tongue at its free end, a locking or engaging plate connected in a pivotal manner to the hinge-plate, and a flat 90 spring fixed to said locking or engaging plate and having its free end disposed and movable between the locking or engaging plate and the tongue of the hinge-plate.

In testimony whereof I have affixed my signature in presence of two witnesses.

GEORGE N. STEERE.
